UNITED STATES PATENT OFFICE.

JOSEPH KORNAS, OF LINDEN, NEW JERSEY, ASSIGNOR TO FELDMAN MACHINE WORKS, INC., A CORPORATION OF NEW YORK.

SEWING MACHINE.

Application filed August 2, 1920. Serial No. 400,665.

To all whom it may concern:

Be it known that I, JOSEPH KORNAS, a citizen of the United States, and resident of Linden, in the county of Union and State of New Jersey, have invented certain new and useful Improvements in Sewing Machines, of which the following is a specification.

The invention relates in general to certain improvements in sewing machines of the type identified in the trade as wiring machines of the zigzag stitch commonly for use in forming diagonal or cross stitching.

The primary object of the invention is to provide a simplified form of construction of such machines in which the number of parts heretofore found necessary in similar machines have been reduced in number with incident economy in manufacturing cost.

Another object of the invention is to provide such a construction in which compactness of parts have been featured, so as to reach into confined spaces in small sized hats, and other structures upon which it is desired to operate, and at the same time to provide in such limited constructions a rigidity and ruggedness of parts to withstand the severe strains incidental to the use of such machines in factory work where the machines are run at high speed.

It is understood that such machines necessarily comprising a number of reciprocating parts, are apt to set up vibration and rattle especially when run at high speed. This vibration tends in known forms of such machines to loosen and wear the parts all of which gives rise to an unpleasant noise which makes such machines unpopular with the operators.

Accordingly, another object of the invention is to provide a type of machine of the class outlined in which movable parts are nicely balanced, securely journalled to fix the axis of rotation and inter-driven in a manner to minimize looseness of play and noise.

With this object in view the disclosure features a construction in which the rotating shafts are provided with long or spaced apart bearings; reciprocating members are closely guided in their movement and at the same time wearing surfaces have been minimized as far as is practicable.

Still another object of the invention is to provide a form of construction in which necessary adjustment may be made quickly,

positively, and accurately and without the necessity of demounting any of the structural parts of the machine.

Various other objects and advantages of the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

In the accompanying drawings:—

Figure 1 is a view in front elevation of a machine of the class described including preferred physical embodiments of the invention.

Figure 2 is a horizontal sectional view taken on the line 2—2 of Figure 1 and showing most of the novel elements of the machine in plan.

Figure 3 is a vertical sectional view taken axially of the main shaft and taken on the line 3—3 of Figure 2.

Figure 4 is an enlarged detail view in axial section of a part of the main shaft and taken on the line 4—4 of Figure 5.

Figure 5 is a transverse sectional view taken on the line 5—5 of Figure 4.

Figure 6 is an enlarged view partly in section of the needle rocker bar frame adjustment taken on the line 6—6 of Figure 1.

In the following description and in the claims, parts will be identified by specific names for convenience of expression but they are intended to be as generic in their application to similar parts as the art will permit.

The device illustrated follows along somewhat conventional designs of the zigzag type of sewing machine now known and includes a supporting base 10, frame 11, together with the usual arm 12, which supports the working parts of the machine. A main shaft 13 is mounted in spaced apart bearings 14 and 15 constituting massive parts of the frame and is provided with the usual driving pulley 16, eccentric 17, which, through the pitman 18, lever 19 and link 20 imparts to the needle bar 21, its vertical or substantially vertical reciprocation. The needle bar 21 is arranged to carry the needle 22 and is mounted to reciprocate in a substantially vertical direction in a needle bar 110

frame 23 mounted to oscillate in a plane parallel with the arm about pivot pin 24 defining a horizontal axis of swing of the frame. It is understood that the needle bar frame is oscillated so that the needle shall be directed first to one side and then the other side of its normal position by means of a link 25, one end of which is pivoted to the needle bar frame adjacent to its upper end through an adjusting connection 26 hereinafter more fully described. The opposite end of the link is pivoted by means of the pin and slot connection 27 to the upper end of a vertically disposed lever 28, which lever is fulcrumed intermediate its length on the pin 29 constituting a horizontally projecting extension from the frame 11 of the machine.

The main shaft, or at least that portion thereof which projects through the bearing 15, is hollowed as shown in Figure 3 and a relatively long solid looper shaft 30 is slidably mounted in the hollow portion and extends beyond the end thereof and beyond the forward face 31 of the bearing 15 which extended portion is provided with the usual looper 32, disposed in the usual operative relation to the needle. The looper shaft is reciprocated axially in the main shaft by the lever 28 which has a roller 33 pivoted to the lower end thereof (shown in Figure 2) fitting in a peripheral groove 34 formed in a split collar 35 slidably mounted on the main shaft. The lever 28 is provided intermediate its ends with a pair of laterally extending parallel and vertically spaced apart bearing flanges 36 and 37 positioned on opposite sides of a cam supporting post 38 extending forwardly from the frame 11. A cam member 39 is rotatably mounted upon the post 38 and is provided with a barrel cam 40 which engages between the flanges and rocks the lever as the cam member is rotated. The cam member is provided with a relatively large gear 41 which is disposed at right angles to and meshes with a gear 42 on the main shaft so as to be driven thereby. The gears 41 and 42 form a reducing gear train and to feature the desideratum for smooth running gears the teeth of the members are of the herring bone type.

The collar 35 is pinned directly to the looper shaft (Figure 5) by means of a screw pin 43 which screw is passed through a slot 44 formed in the main shaft.

One of the features of this disclosure is to provide a broad bearing surface between the sleeve and the driving shaft and for this purpose the shaft is provided on one side with a flat surface 45 and the sleeve is partially split in advance of the groove to form a segmental piece 46 with a flat surface engaging the flat surface on the main shaft so as to extend over a material

area thereof. The segmental piece is secured in position by means of set screws 47. It is understood that the flat surface 45 extends lengthwise of the main shaft for a distance to accommodate the sleeve in its limit of movement in both directions under the reciprocatory action of the lever 28.

The portion of the main shaft immediately in advance of the flattened portion is provided with a relatively short eccentric cam 48 for actuating a feeder reciprocating mechanism 49 secured to the feeder 50 as is usual in such constructions. The length of the cam is limited to the width of the arm 49' engaged thereby and is provided on its left side with a bearing flange 48'. A screw 50' is passed through the thick part of the eccentric cam and into the main shaft so as to transmit rotary movement from the shaft to the cam. The portion of the shaft between the cam 48 and the rear side of the bearing 15 is provided with a slot 51 and a grooved sleeve 52 is slidably mounted on the main shaft and is provided with a screw 53 which passes through the slot 51 and engages the looper shaft so that the reciprocations of the looper shaft are communicated to the grooved sleeve.

The upper face of the bearing 15 is provided with a longitudinally extending needle plate guideway 54 within which is fitted the body portion 55 of a needle plate 56, the rear end of which plate is provided with a depending pin 57 designed to engage in the groove 58 formed on the sleeve 52. The forward end of the needle plate is provided with an upwardly extending projection 59 provided with a needle receiving hole 60. The needle plate is demountably held in position by means of a work plate 61 fastened to the bearing 15 by means of locating pins 62 and a set screw engaging the screw hole 63. The work plate extends forwardly of the bearing 15 so as to overlap the feeder and looper as is usual in such structures. The work plate constitutes a means for securing the needle plate in position in its guideway 54. The work plate is provided with two slots or rather with an L-shaped opening 64 in one slotted portion 65, of which the projection 59 from the needle plate is designed to reciprocate and to be guided substantially free of vibratory movement. The other slotted portion 66 is designed to contain the feeder 50 which likewise is mounted for reciprocatory movement transversely of the length of the main shaft and designed likewise to be held against vibratory movement while free to reciprocate in its usual functional manner.

With reference to the adjusting connection 26 (Fig. 6) an eccentric pin 67 connects the link 25 with the rocking needle bar frame. The pin is provided with a spherical head 68 and socket 69 formed

partly in the front face of the link 25 and partly in a front bearing plate 70. The plate 70 is fastened by means of screws 71 to the front of the link and is provided with an opening 72 extending through and into the socket to permit a screw driver to reach to the head of the eccentric pin so as to rotate the same and thus adjust the relation between the rocking needle bar frame and the link.

In operation it is to be understood that the device works substantially as is usual in operations of zig-zag stitching machines of the type disclosed, in which a long dwell follows each lift of the needle and the looper, together with the needle plate, is shifted with the shifting of the needle. In the present disclosure power is taken off the main shaft through the reduced gear connection to reciprocate the upstanding lever, the upper end of which lever is connected directly to the rocking needle bar frame and the lower end of the lever is connected through the sliding collar with the looper bar. It is appreciated that in this way the looper shaft and the rocker arm reciprocate in synchronism. Power is transmitted directly from the main shaft to the looper bar housed therein through the broad bearing connection provided by the split sleeve 35 so that the looper shaft is both reciprocated and rotated through the agency of this sleeve. As the looper shaft is contained within the main driving shaft a long bearing is provided therefor thus tending to minimize relative vibratory movement and the compact construction resulting therefore permits of the use of a relatively narrow work plate.

The parts on the main shaft between the long bearings 14 and 15 are so apportioned among the parts taking power off of the shaft that all of this space is completely utilized thus tending to reduce the length of the machine as a whole and to take power off of the shaft at points most conveniently available to the parts actuated therefrom.

While I have shown and described, and have pointed out in the annexed claims, certain novel features of my invention, it will be understood that various omissions, substitutions and changes in the form and details of the device illustrated and in its operation may be made by those skilled in the art without departing from the spirit of the invention.

Having thus described my invention, I claim:—

1. In a sewing machine of the zigzag type, the combination of a main shaft, a looper shaft slidably journaled therein and having an engagement with the main shaft whereby it is rotated therewith and is free to move longitudinally with respect thereto, an upstanding lever fulcrumed intermediately

70

ate its ends, a needle bar frame pivoted to rock about a horizontal axis and thus cause a needle bar and needle carried thereby to trace a zigzag stitch, a link connection between the upper end of the lever and said needle bar frame, a cam driven from the main shaft and connected to said lever intermediate its ends to rock the same, and means connecting the lower end of the lever with the looper shaft to reciprocate the same longitudinally as it is rotated directly by the main shaft.

2. In a sewing machine of the zigzag type, the combination of a main shaft, a looper shaft slidably journaled therein and having an engagement with the main shaft whereby it is rotated therewith and is free to move longitudinally with respect thereto, an upstanding lever fulcrumed intermediate its ends, a needle bar frame pivoted to rock about a horizontal axis and thus cause a needle bar and needle carried thereby to trace a zigzag stitch, a link connection between the upper end of the lever and said needle bar frame, a cam engaging the lever to rock the same, a reducing gear connection between the cam and the main shaft and means connecting the lower end of the lever with the looper shaft to reciprocate the same longitudinally as it is rotated directly by the main shaft.

3. In a sewing machine of the zigzag type, the combination of a main shaft, a looper shaft slidably journaled therein and having an engagement with the main shaft whereby it is rotated therewith and is free to move longitudinally with respect thereto, an upstanding lever fulcrumed intermediate its ends, a needle bar frame pivoted to rock about a horizontal axis and thus cause a needle bar and needle carried thereby to trace a zigzag stitch, a link connection between the upper end of the lever and said needle bar frame, a cam driven from the main shaft and connected to said lever intermediate its ends to rock the same, means connecting the lower end of the lever with the looper shaft to reciprocate the same longitudinally as it is rotated directly by the main shaft and a needle plate mounted for reciprocatory movement with the needle bar frame and operatively connected with the looper shaft to move therewith.

4. In a sewing machine of the zigzag type, the combination with a support and mechanism mounted for reciprocatory movement, of a main shaft journaled in said support and providing a support for the reciprocating mechanism, a gear on said shaft, a lever provided with a cam engaging extension projecting laterally of its fulcrum, a cam member geared to the main shaft gear and engaging said extension to rock the lever and means including a split sleeve slidably mounted on the main shaft, pinned to the

120
125
130

same to turn therewith and provided with a peripheral groove for receiving one end of the lever and connecting the lever with said reciprocatory mechanism on the main shaft 5 to cause the same to function.

5. In a sewing machine of the zigzag type, the combination of a main shaft, a looper shaft slidably mounted therein and connected to rotate therewith, a power pulley 10 fixed to said shaft, a cam controlled lever, a gear on said shaft, a needle bar frame operatively connected to be rocked from said lever, a collar slidably mounted on the main shaft actuated by said lever and operatively 15 connected to the looper shaft to reciprocate the same, a feeder actuating cam on said main shaft, a needle plate actuating cam slidably mounted on said main shaft and a pin passing through the main shaft and connecting the cam with the looper shaft to reciprocate therewith.

6. In a sewing machine of the zigzag type, the combination of a main shaft, means for rotating the shaft, a looper shaft slidably 25 mounted in the main shaft and having a long bearing therein, mechanism for reciprocating the looper shaft from the rotary movement of the main shaft, said mechanism including a yoke collar slidably mounted on 30 the main shaft, a lever pivoted intermediate its length and with one end engaged in the collar to reciprocate the same, means for fixing the collar to the looper shaft, means for driving the collar from the main shaft, a 35 gear on the main shaft and a cam driven from said gear and operatively connected to the lever to reciprocate the same.

7. In a sewing machine of the zigzag type, the combination of a main shaft, means for 40 rotating the shaft, a looper shaft slidably mounted in the main shaft and having a long bearing therein, mechanism for reciprocating the looper shaft from the rotary movement of the main shaft, said mechanism including a yoke collar slidably mounted on 45 the main shaft, and having a peripheral groove, a lever engaging in said groove to reciprocate the collar, a cam controlled means driven from the main shaft and operatively 50 connected to the lever to reciprocate the same, means for fixing the collar to the looper shaft and means for driving the collar from the main shaft, said last named means including a broad bearing connection 55 between the main shaft and collar.

8. In a sewing machine of the zigzag type, the combination of a main shaft, a looper shaft journaled therein for longitudinal movement, a part of said main shaft provided on the outer side thereof with a flat surface, a split sleeve slidably mounted on the main shaft and including a segmental part with a flat face engaging the flat surface on the shaft thereby to provide a broad 60 bearing between the sleeve and shaft to

transmit rotary torque from one to the other, means connecting the sleeve with the looper shaft and means driven from the main shaft for reciprocating said sleeve and its connected looper shaft. 70

9. In a sewing machine of the zigzag type, the combination of a main shaft provided with a longitudinally extending slot, a looper shaft mounted in the main shaft for relative longitudinal movement, a yoke sleeve slidably mounted on the main shaft and split along a plane offset from its axes of rotation, means passing through the slot for connecting the sleeve and looper shaft thereby to reciprocate the looper shaft from the sleeve, means for reciprocating the yoke sleeve, and said sleeve and shaft having a flat contacting portion providing a broad bearing connection between the sleeve and main shaft to transmit the rotary movement 85 of the shaft to the sleeve, the flat contacting portion between the sleeve and main shaft being offset from the split between the parts of the yoke sleeve.

10. In a sewing machine of the zigzag 90 type, the combination of a main shaft, a looper shaft journaled therein for relative longitudinal movement, means including a sleeve slidably mounted on the main shaft, directly rotated thereby and pinned to the looper shaft for reciprocating the looper shaft from the main shaft, a needle plate mounted for reciprocatory movement, a plate controlling sleeve slidably mounted on the main shaft connected to the looper shaft and 100 to the needle plate to cause the needle plate to reciprocate with and by the looper shaft.

11. In a device of the class described, the combination of a frame, a main shaft journaled in the frame, a looper shaft having a long bearing in the main shaft, means for rotating the main shaft, a rotary driving connection between the main shaft and the contained looper shaft, means driven from the main shaft for reciprocating the looper shaft and a needle plate mounted for reciprocatory movement and connecting means passing through the main shaft for actuating the needle plate from the looper shaft. 110

12. In a device of the class described, the combination of a frame, a main shaft journaled in the frame, a looper shaft having a long bearing in the main shaft, means for rotating the main shaft, a rotary driving connection between the main shaft and the contained looper shaft, means driven from the main shaft for reciprocating the looper shaft, a needle plate mounted for reciprocatory movement and connecting means passing through the main shaft for actuating the needle plate from the looper shaft and feeder actuating mechanism disposed on the main shaft between said reciprocating needle plate connecting means and the looper shaft reciprocating means. 125 130

13. In a device of the class described, the combination of a support provided with a needle plate guideway, a needle plate slidably mounted in said guideway and provided with an extension having a needle receiving hole therein, a work plate positioned on said support and acting to secure the needle plate in the guideway, said work plate provided with a slot for receiving said extension from the needle plate, a main shaft journaled in the support, a looper shaft journaled in the main shaft, a looper carried by the looper shaft below the work plate and means for reciprocating the needle plate from the looper shaft.

14. In a device of the class described, the combination of a support provided with a needle plate guideway, a needle plate slidably mounted in said guideway and pro-

vided with an extension having a needle receiving hole therein, a work plate positioned on said support and acting to secure the needle plate in the guideway, said work plate provided with a slot for receiving said extension from the needle plate, a main shaft 20 journaled in the support, a looper shaft journaled in the main shaft, a looper carried by the looper shaft below the work plate, means for reciprocating the needle plate from the looper shaft, said work plate 25 also provided with a feeder slot, a feeder mounted to reciprocate in said feeder slot and means for actuating the feeder.

Signed at New York city, in the county of New York and State of New York, this 35
26th day of July, A. D. 1920.

JOSEPH KORNAS.
